UNITED STATES PATENT OFFICE.

JOHN EDMUND PERRY, OF SHARON, PENNSYLVANIA, ASSIGNOR TO VALLEY MOULD & IRON CORPORATION, OF SHARPSVILLE, PENNSYLVANIA, A CORPORATION OF NEW YORK.

INGOT MOLD AND METHOD OF CASTING.

Application filed June 25, 1921. Serial No. 480,304.

To all whom it may concern:

Be it known that I, JOHN E. PERRY, a citizen of the United States, residing at Sharon, in the county of Mercer, State of Pennsylvania, have invented certain new and useful Improvements in Ingot Molds and Methods of Casting, of which the following is a specification.

This invention relates broadly to metallurgy and more specially to a method and a mold for casting steel ingots.

A primary object of the present invention is to provide a separable closed mold for casting steel ingots with the parts arranged 15 to separate in such manner as to uncover the ingot and permit the same to be readily lifted from the mold.

A further object of the present invention is a mold of the character specified in which 20 the mold separates diagonally to permit the ingot to be removed without the necessity of providing draught on the sides of the ingot.

Another object of the present invention 25 is an ingot mold of the character specified wherein the cover is adapted to be lifted from the ingot when the ingot is solidified and permit the ingot to rest on a flat side of the mold in such manner that the ingot may 30 be lifted or dumped from the remaining half of the mold.

Another and important object of the present invention is a covered ingot mold for horizontal ingots and wherein the mold is 35 arranged to separate in such manner as to release the runner tile from the mold so that the runner tile goes with the ingot when the ingot is stripped from the mold.

Another and more specific object of the 40 present invention is an ingot mold of the character specified and wherein the mold is adapted to cast horizontal steel ingots in a closed mold body with the sides of the mold being separated on planes diagonal to the 45 matrix and with the foot of the mold separating also on a diagonal line and the head of the mold separating adjacent the runner tile channel.

Another and primary object of the present 50 invention is the method of casting steel ingots in shallow molds which comprises inclining the lower surface of the matrix in such manner as to form the first portion of the molten steel into a pool adjacent the incoming stream of molten steel.

Another object of the present invention is the method of casting steel ingots in horizontal molds which comprises introducing the molten stream adjacent one end of the mold and arranging the matrix walls of the 60 mold in such manner that a molten steel pool forms first adjacent the runner tile where the molten steel is entering the mold.

Another and important object of the present invention is the method of casting steel 65 ingots in horizontal molds which comprises causing a molten steel pool to begin to form beneath the incoming molten steel stream so that the molten steel stream contacts directly with the mold wall only at the initial entrance of the molten steel into the mold and after that time the stream pours upon or into the pool of molten steel in the mold which covers and protects the mold wall.

Another and important object of the present invention is the method of casting horizontal ingots in covered chill molds, which 70 method comprises providing the matrix of the mold with the walls arranged so that the lowest portion of the matrix is adjacent the 75 stream of incoming molten steel and withdrawing mold gases from the mold along a mold joint in the highest portion of the matrix.

Another and important object of the present invention is the method of casting horizontal ingots in a closed horizontal chill mold, which method comprises forming an initial pool of molten steel by the first steel 80 to enter the mold and causing the on-coming molten steel to pour upon and into said pool and causing mold gases to escape from the highest portion of the mold at a point opposite to and remote from said pool.

A still further object of the present invention is a mold of the character specified and wherein the side walls of the mold taper from the foot of the mold toward the head thereof.

A still further object of the present invention is a closed horizontal mold comprising two pieces adapted to separate in such manner as to open the runner tile channel whereby the ingot and runner tile may be stripped 90 from the mold.

Other and further objects of the present invention will in part be obvious and will in part be pointed out in the specification hereinafter following by reference to the accompanying drawings wherein like parts are 100 105 110

represented by like characters throughout the several figures thereof.

Realizing that the present invention may be embodied in constructions other than those herewith illustrated and described, it is desired that the disclosure herewith shall be understood as being illustrative and not to be taken in the limiting sense.

Figure 1 is a view showing the mold assembled;

Figure 2 is a section on line 2—2 Figure 7;

Figure 3 is an end view of the head of the mold;

Figure 4 is an end view of the foot of the mold;

Figure 5 is a perspective view of the top member separated vertically from the bottom member.

Figure 6 is a perspective view of the top member separated horizontally from the bottom of the mold.

Figure 7 is a plan view of the head end of the mold;

Figure 8 is a longitudinal section of the mold and illustrates the method of pouring and shows the beginning of the formation of the initial pool.

Figure 9 is a cross-sectional view illustrating the method and shows the on-coming steel stream pouring upon the initial pool.

Heretofore in the art the most common type of ingot mold has been the vertical integral open mold in which the molten steel was poured into the open mouth or upper end and when the ingot solidified it was stripped from the mold by forcing the ingot and mold relative to each other in longitudinal directions. In order to obtain clearance for this stripping operation the ingot was duly tapered. For many purposes a parallel sided ingot is more desirable than a tapered ingot. It has been proposed to cast ingots horizontally and to provide multi-part molds, that is, molds wherein inverted troughs could be used on suitable stool plates or wherein stool plates were dispensed with and a plurality of parts were provided for the mold itself. In such constructions where ingots have been cast in covered molds it has been necessary to use runner tiles of fire-clay or similar material. These runner tiles have usually extended through a portion of the mold and there is a liability of the runner tile acting to lock the ingot to the mold due to a portion of the tile extending through an opening in the wall of the mold. When the ingot is poured there is usually a root of metal left in the runner tile and this root is sometimes difficult to break. The breaking operation is liable to injure the mold. Furthermore, if for any reason the ingot tends to stick in a trough type of mold it is exceedingly difficult to dislodge the ingot from the mold. It has also been proposed to make horizontal ingot molds of a number

of pieces such as hinged sides, etc., and with pieces and parts adapted to be fastened together with a number of clamps, wedges, or the like. Such constructions increase the number of parts on the casting floor, thereby increasing the liability of accidents and also the liability of crippling equipment by loss of small, yet important parts.

In the constructions heretofore proposed for the casting of horizontal ingots in chill molds the molten stream has been permitted to strike the matrix wall for a considerable length of time and until a pool of molten steel was formed of such size as to receive the on-coming stream. Since the molds are of cast iron the continued impinging of fresh molten steel against one spot on the matrix side wall eventually raised the temperature of that spot to such a point that the cast iron in the side wall was cut away by the hot molten steel. This tended to quickly destroy the molds and further tended to leave a rough spot on the ingot, both of which faults were serious.

The present invention overcomes the difficulty of the known prior art by providing a horizontal mold of the covered or closed type, which mold is formed of two pieces so constructed that the lines of separation are arranged relatively to the shape and dimensions of the matrix so that there are no parallel sides or reentrant angles in either piece of the mold. It therefore follows that there is no possibility of the ingot sticking during the stripping operation and therefore the ingot can always be removed without trouble. The present invention furthermore contemplates the arrangement of the separation planes in such manner that the weight of the upper piece of the mold automatically holds the mold together so that under normal conditions no clamps are required. The present invention furthermore comprises a two part covered or closed mold with the lines of separation arranged to completely free the runner tile so that the runner tile and root of the ingot are stripped from the mold with the ingot in order that the runner tile may be easily broken away after the ingot is out of the mold. The outlet for the mold gases in the present mold comprises the joints between the pieces of the mold, and the upper long joint which leads from the upper corner of the mold forms an admirable outlet at the highest portion of the mold.

The present invention also overcomes the difficulties heretofore encountered in casting in horizontal molds, by providing a method wherein the mold is inclined to the horizontal and with the pouring end of the mold comprising the lowest part of the matrix of the mold. By means of this method the initial entrance of the steel into the matrix forms a pool exactly at the spot where the steel stream enters the mold so

that the on-coming steel strikes the surface of this pool, which causes a convection movement or currents of the pool to move toward the stream of on-coming molten steel. Since the steel in the pool rapidly loses heat due to the chill of the mold walls the steel in the convection currents is much colder than the on-coming molten steel, so therefore the fresh molten steel from the ladle is kept away from the side wall of the matrix and consequently a chilled skin or shell begins to form adjacent the matrix walls which so covers and protects these walls that the danger of cutting the walls by the molten stream is completely obviated. Furthermore the present invention contemplates the line of separation of the mold to occur on the diagonal of the mold. It has been found that the separation joints may be open to a considerable extent without any danger of the molten steel escaping through these joints so that therefore the separation joints comprise ample means for escape of the mold gases. In view of the fact that the present invention contemplates a continuous joint along the upper diagonal edge of the mold and that the mold shall be set with this diagonal edge or dihedral angle of the matrix at the highest part of the matrix, the entire upper corner of the matrix comprises a gas outlet.

In the manipulation of molds of the present character the molds may either be set on the casting floor or may be set on flat cars. After the molds are filled and the ingot sufficiently cool, an empty lower half is set adjacent the first mold to be stripped. The crane that lifts the cover or top portion of the first mold sets it over on the open lower half. A runner tile is then dropped in place in the re-set mold, and a complete mold is now ready for another casting operation. The runner tile may be dropped in place while the stripping crane is tripping or lifting the ingot from the lower half of the mold, which has just been uncovered so that a series of operations may be carried on simultaneously. The stripping operation can be carried out in many ways. It may be done by means of one crane, it may be done by means of two cranes wherein while one crane is carrying an ingot to the soaking pit, or wherever the ingot is to be deposited, another crane may be setting up a fresh mold from the one which was just stripped. The stripping operation of the first mold leaves a base open and ready to receive the upper half or top of the second mold, and in this manner the operations may be carried on in series so that the taking down of one mold automatically sets up a new mold. Where desired the train or cycle of molds may be of such length as to bring the re-set molds past the pouring station and the operations

may comprise a continuous series which may be carried on for as long a period as may be desired.

Referring now to the drawings, the lower half A of the mold may comprise a base 1 which is integral with the side wall 2 and preferably at substantially right angles thereto. The upper edge of the side wall 2 is arranged in such manner as to provide a projection or interlocking member adapted to interfit with the top. These interlocking sides may be formed in various ways, preferably to provide a projection on one member and a reentrant angle on the other member. In the form disclosed in the drawings the upper edge of the side wall 2 is inclined outwardly and downwardly as at 4 and the edge wall of the base 1 preferably is inclined outwardly and upwardly as at 5. The foot wall 6 of the under half of the mold extends diagonally between the inclined walls 4 and 5 so that the line of separation of the end or foot wall is substantially that of a reversed Z-shape. However, the upper end of the foot wall as at 7 follows the conformation of the matrix in order to insure complete drainage of mold gases by means of the joint at 7 adjacent this high corner of the mold. The head of the lower half of the mold preferably comprises a substantially vertical wall 8 which is provided with an offset portion 9 that forms the side wall and back of a channel for a suitable runner tile 21. The separation line on this lower half of the mold extends vertically along one side of the runner tile channel as at 11. Preferably a slight bead 12 is provided along the lower edge of the line of separation marked by the juncture of the outwardly and upward separation plane 5 and the bottom wall. This bead tends to round the edge of the ingot and has a tendency to prevent fins from forming at this joint.

The upper half B of the mold is substantially a counterpart of the lower half and comprises a top wall 14 and a side wall 15 which are joined together at the foot by a diagonal end wall 16. The edge 17 of the top wall extends downwardly and outwardly to provide a surface adapted to set on and interfit with the surface 4 of the bottom half A of the mold. The side wall 15 likewise is provided with an edge 18 which is adapted to interfit with and comprise the complement to the surface 5 on the base wall. The head of the top half B is arranged with a vertical depending wall 19 adapted to fit against the wall 11 and leave a suitable opening 20, (Fig. 1) for the runner 21, (Figs. 2 and 3). The upper half B of the mold is provided with suitable staples 22 for lifting or handling the parts. The staples 24 in the foot and staples 25 in the head end portions may be used for handling

and at the same time may provide keepers through which suitable bars 26 may be set and when wedges 27 are driven under the bars to comprise a friction lock to hold the parts together when such locking is deemed desirable or necessary. In practice no locking is ordinarily required, since the separation planes between the base A and the top half B are so arranged as to provide projections and reentrant angles, it follows that the parts automatically set together due to gravity and it is only under rare conditions that locking together is needed. The upper half is provided with a bead 28 which extends along the edge of the surface 17 and performs the same function as the bead 12 in the base, namely, to round the edge of the ingot and prevent the formation of fins. The runner tile 21 may comprise a combined fountain and runner tile and preferably is provided with an elongated opening 29 which extends vertically so that the molten steel coming through the runner tile will cause a vertical mixing action in the pool of molten steel in the mold. Since the mold is diagonally inclined the mixing action is accentuated because the stream C falls in a diagonal manner and is flattened and distorted by gravity action.

This molten pool D forms adjacent the runner tile in view of the fact that the lowest portion of the matrix is adjacent this end of the mold, since the mold is inclined by saddles 30 and 31, or by other means, in both directions to the horizontal. This causes a triangular pool to quickly form from the first molten steel in the mold and thereby obviates all danger of cutting the mold by the steel stream. The side walls of the mold may be arranged in various ways but preferably are tapered so that the heat absorbing capacity at the foot of the mold is considerably greater than the heat absorbing capacity at the head of the mold.

This arrangement causes the crystallization or freezing of the molten steel to progress from the foot of the mold toward the head of the mold. As the separation joints of the mold are on the corners of the mold, and as the mold is diagonally inclined, the top corner where the separation joint occurs is the highest part of the mold and thus ample provision is made for the escape of mold gases.

Furthermore it will be noted that the separation of the upper half B from the lower portion A is arranged along the corners of the matrix portion of the mold so that the matrix side walls taper away from these joints. Since the ends of the ingot need not necessarily be plane, it is preferable that the end walls of the matrix also slightly slope or taper toward the separation joints, so that the top half B of the mold im-

mediately clears the ingot when the top half is lifted, and the ingot immediately clears the lower half A when the ingot is lifted. By this construction it will be noted that the parts may be separated with the least amount of force necessary under the circumstances. In other words, it is not necessary to break any roots or strip the ingot from any long parallel friction surface, so consequently the forces necessary for the stripping operation are only slightly in excess of the forces necessary to overcome gravity, since the parts are lifted and the stripping operation is carried on without destructive effort, that is, without necessity of breaking any roots or fins, or breaking any nibs, or humps which may form in faults or flaws in the matrix of the side wall.

From the foregoing description it will appear that when the upper half of the mold is lifted off, the ingot lies with two sides exposed and with sufficient end surface uncovered to permit crane hooks to easily lift the ingot from the base or lower half. Since the tile is adapted to go with the ingot the root is short and a very small amount of scrap occurs, and therefore substantially the complete ingot is adapted for rolling without cropping, and the only waste or scrap is the metal which forms the root in the runner tile.

Having thus described my invention, what I claim is:

1. An ingot mold for casting steel ingots horizontally comprising when assembled a closed chill mold with the longitudinal lines of separation arranged at the corners of the matrix portion of the mold and with the end lines of separation extending diagonally of the mold at one end and transversely of the mold at the other end.

2. An ingot mold for casting steel ingots horizontally comprising when assembled a closed chill mold with the longitudinal joints of separation arranged at the corners of the matrix portion of the mold said joints being arranged to form a gravity lock and with the end joints of separation extending diagonally of the mold at the foot of the mold and transversely of the mold at the head of the mold.

3. An ingot mold for casting steel ingots horizontally comprising when assembled a closed chill mold having the thickest walls at the foot of the mold with the longitudinal lines of separation arranged at the corners of the matrix portion of the mold and with the end lines of separation extending diagonally of the mold at one end and transversely of the mold at the other end.

4. An ingot mold for casting steel ingots horizontally comprising when assembled a closed chill mold with the longitudinal lines of separation arranged at the corners of

the matrix portion of the mold and with the end lines of separation extending diagonally of the mold at one end and transversely of the mold at the other end, and 5 means to set said mold with the head of said mold lower than the foot thereof.

5. An ingot mold for casting steel ingots horizontally comprising when assembled a closed chill mold having the thickest walls 10 at the foot of the mold with the longitudinal joints of separation arranged at the corners of the matrix portion of the mold said joints being arranged to form a gravity lock and with the end joints of separation extending diagonally of the mold at the foot of the mold and transversely of the mold at the head of the mold.

6. An ingot mold for casting steel ingots horizontally comprising when assembled a closed chill mold with the longitudinal joints of separation arranged at the corners of the matrix portion of the mold said joints being arranged to form a gravity lock and with the joints of separation extending diagonally of the mold at the foot of the mold and transversely of the mold at the head of the mold, and means to set said mold with the head of said mold lower than the foot thereof.

30 7. A mold for casting steel ingots horizontally and including a pair of complementary mold sections adapted when assembled to form a closed chill mold, the top section comprising the top, one side, and a portion of both ends of the mold, so that when the top section is removed, the end portions of the ingot are uncovered whereby the ingot may be lifted from the other section without destructive effort.

40 8. A mold for casting steel ingots horizontally and comprising a pair of complementary mold sections adapted when assembled to form a closed chill mold, with the sections arranged in such manner that the upper joint is at the highest portion of the matrix and the lower joint is in the lowest portion of the matrix so that when the top section is raised after the ingot has been cast the top, one side, and a portion 50 of both ends of the ingot are uncovered whereby the ingot may be lifted from the other section without destructive effort.

55 9. A mold for casting steel ingots horizontally and comprising a pair of complementary mold sections comprising a bottom section and a top section adapted when assembled to form a closed chill mold, the upper joint being downwardly inclined, and the lower joints being upwardly inclined, 60 with the sections arranged in such manner that the upper joint is at the highest portion of the matrix and the lower joint is in the lowest portion of the matrix so that when the top section is raised after the in-

got has been cast the top, one side, and a portion of both ends of the ingot are uncovered whereby the ingot may be lifted from the other section without destructive effort and with a runner tile carried by the lower section.

70

10. An ingot mold for casting steel ingots horizontally comprising a plurality of sections which when assembled form a closed chill mold having a matrix portion substantially rectangular in cross-section, with the joints arranged to permit the escape of mold gases from the highest portion of the matrix and wherein all the walls of both sections are inclined toward the separating joints in such manner as to provide clearance to enable the mold to be disassembled and the ingot lifted therefrom without destructive effort.

75

11. An ingot mold for casting steel ingots horizontally comprising a plurality of sections which when assembled form a closed chill mold having a matrix portion substantially rectangular in cross-section, means to permit molten steel to be poured into one end of the matrix, and with the walls of said mold being arranged to permit the escape of mold gases from the highest portion of the matrix and wherein all the walls of both sections are inclined toward the separating joints in such manner as to provide clearance to enable the mold to be disassembled and the ingot lifted therefrom without destructive effort.

80

12. An ingot mold for casting steel ingots horizontally comprising a plurality of sections which when assembled form a closed chill mold having a matrix portion substantially rectangular in cross-section, with the joints arranged to permit the escape of mold gases from the highest portion of the matrix, said walls being thickest at the foot of the mold and wherein all the walls of both sections are inclined toward the separating joints in such manner as to provide clearance to enable the mold to be disassembled and the ingot lifted therefrom without destructive effort.

85

13. An ingot mold for casting steel ingots horizontally comprising a plurality of sections which when assembled form a closed chill mold having a matrix portion substantially rectangular in cross-section, with the joints arranged to permit the escape of mold gases from the highest portion of the matrix and wherein all the walls of both sections are inclined toward the separating joints in such manner as to provide clearance to enable the mold to be disassembled and the ingot lifted therefrom without destructive effort and means to set said mold with a diagonal downward incline toward the head of the mold.

90

14. An ingot mold for casting steel ingots

95

100

11

1

1

horizontally comprising a plurality of sections which when assembled form a closed chill mold having a matrix portion substantially rectangular in cross-section, means to 5 permit molten steel to be poured into one end of the matrix, and with the joints of said mold being arranged to permit the escape of mold gases from the highest portion of the matrix and wherein all the walls 10 of both sections are inclined toward the separating joints in such manner as to provide clearance to enable the mold to be disassembled and the ingot lifted therefrom without destructive effort, and means to set 15 said mold with a diagonal downward incline toward the head of the mold.

15. A mold for casting steel ingots horizontally, said mold comprising a pair of complementary mold sections adapted to support at one end of the matrix a suitable runner tile, the matrix walls of said sections being sloped toward the separating joints in such manner that a relative movement between either section and the ingot at right 25 angles to the axis of the ingot produces clearance between the ingot and the related section.

16. A mold for casting steel ingots horizontally, said mold comprising a pair of complementary mold sections adapted to support at one end of the matrix a suitable runner tile, the matrix walls of said sections being sloped toward the separating joints in such manner that any relative vertical 30 movement between either section and the ingot produces clearance between the ingot and the related section, and a runner tile carried in a channel between the sections in such manner as to be freed when there is a relatively vertical movement between the ingot and either section.

17. A closed mold for casting horizontal ingots said mold comprising a pair of complementary members separated on a diagonal of the matrix, one of said members forming the bottom and one side of the mold and the other of said members forming the top and opposite side of said mold, the last mentioned member also comprising part of the end portions of the mold.

18. A mold for casting horizontal ingots said mold comprising a pair of complementary members, one of said members forming the bottom and one side of the mold and the other of said members forming the top and opposite side of said mold, and a runner tile channel having two side walls on one section and the other side wall on the other section.

19. A horizontal mold for casting steel ingots comprising a plurality of sections, one of said sections being adapted to carry a runner tile and the other of said sections being adapted to support one side of the

runner tile in such manner that when the 65 last mentioned section is removed after the ingot has been cast the runner tile is free to leave the first mentioned section when the ingot is stripped therefrom.

20. A horizontal mold for casting steel 70 ingots comprising a plurality of sections, one of said sections being adapted to carry a runner tile, a runner tile on said section and being provided with an elongated opening adapted to deliver a flat stream of 75 molten steel, the other of said sections being adapted to support one side of the runner tile in such manner that when the last mentioned section is removed after the ingot has been cast the runner tile is free to leave 80 the first mentioned section when the ingot is stripped therefrom.

21. A horizontal closed mold for casting steel ingots said mold comprising a plurality of sections, one of said sections comprising an integral cast iron member having a base portion and a side wall connected at the foot of the mold by an inclined end wall and with the head of the mold provided with a portion of an end wall extended between the said side wall and the base, and the other section being adapted to close the first mentioned section in such manner as to provide a full chill mold with an elongated matrix having a substantially 95 rectangular cross section.

22. A horizontal mold for casting steel ingots, said mold comprising a base section and a cover section, the base section being formed with a bottom wall, and a 100 side wall, the said bottom wall and said side wall being joined at the foot of the mold by a diagonal wall with a portion of the diagonal wall having an edge which corresponds to the top surface of the matrix 105 wall of the mold, the bottom wall and the side wall being joined at the head of the mold by an end wall adapted to form a portion of a channel for a runner tile, said cover section comprising a top wall, and a 110 side wall, with end walls joining the said top wall and side wall in such manner as to cooperate with the walls of the base section to form a completed ingot mold when the parts are assembled.

23. A horizontal mold for casting steel ingots, said mold comprising a base section and a cover section, the base section being formed with a bottom wall, and a side wall, the said bottom wall and said side wall being joined at the foot of the mold by a diagonal wall with a portion of the diagonal wall having an edge which corresponds to the top surface of the matrix 120 wall of the mold, the bottom wall and the side wall being joined at the head of the mold by an end wall adapted to form a portion of a channel for a runner tile, said 125

cover section comprising a top wall, and a side wall, with end walls joining the said top wall and side wall in such manner as to cooperate with the walls of the base section to form a completed ingot mold when the parts are assembled, means to support said mold with the head low so that the pool of molten steel forms initially adjacent the entering stream.

24. The method of casting steel ingots in horizontal molds having axes substantially horizontal which comprises causing a long shallow pool of molten steel to form from the initial steel entering the mold and then causing the subsequent additions of steel to said mold to pour into or upon said pool.

25. In casting steel ingots in a horizontal covered chill mold provided with a runner adapted to direct the stream into one end of the matrix of the mold, the method which comprises arranging the matrix in such manner that a relatively long shallow steel pool forms first adjacent said runner whereby the stream of molten steel falls upon said pool until the matrix is filled to the height of the inlet opening of the runner.

26. In casting steel ingots in a horizontal covered chill mold having a matrix prismatical in cross section and provided with a runner adapted to direct the stream into one end of the matrix of the mold, the method which comprises arranging the matrix with an angular corner thereof as the lowest portion of the matrix and adjacent the runner, and pouring the steel to form an initial steel pool adjacent said runner whereby the stream of molten steel falls upon said pool until the matrix is filled to the height of the inlet opening of the runner.

27. In casting steel ingots in horizontal closed chill molds provided with a runner tile for directing the stream of molten steel directly from the ladle into the end of the matrix of the mold, which method comprises causing the formation of an initial pool of molten steel to form over the portion of the mold in a line with the trajectory of the stream of molten steel to prevent direct contact of the fresh molten steel with the side walls of the matrix and chilling the steel in contact with the mold walls.

28. In casting steel ingots in horizontal closed chill molds provided with a runner tile for directing the stream of molten steel into the end of the matrix of the mold which method comprises causing the formation of a pool of molten steel to initially form over the portion of the mold in a line with the trajectory of the stream of molten steel with the side walls of the matrix, chilling the

molten steel in contact with the mold walls, 85 and to cause convection currents of cool molten steel to move toward the incoming stream.

29. The method of casting steel ingots in a horizontal closed chill mold which method 70 comprises arranging the mold in such manner that the first steel in the mold forms a pool directly beneath the stream of the molten steel and in such manner as to cause convection currents of cool molten steel to 75 move toward the surface of the pool, whereon the stream of fresh steel strikes the surface of the pool, and chilling the molten steel in contact with the mold walls.

30. In casting steel ingots in substantially horizontal closed chill molds the method which comprises protecting the matrix walls from direct contact with the stream of fresh molten steel by forming an initial pool and chilling the under portions thereof before 85 the temperature of said walls is raised sufficiently to permit cutting of the walls by the stream of fresh molten steel.

31. The method of casting horizontal ingots and the like which comprises protecting the matrix side walls from cutting action due to the stream of molten steel entering the mold by covering said walls with a pool 90 of molten steel and chilling the under portions thereof.

32. The method of casting steel ingots in a horizontal chill mold having a substantially horizontal axis, which method comprises protecting the side walls by a film of material of less temperature than the temperature of the molten steel in the feeder stream. 100

33. The method of protecting the side walls of horizontal molds from a falling runner stream of molten steel during the 105 casting of steel ingots and the like which method comprises providing a liquid protecting medium between the runner stream and said side walls which medium is of a lesser temperature than the steel in the 110 feeder stream of the molten steel.

34. The method of protecting the side walls of horizontal molds during the casting of steel ingots and the like which method comprises providing a protecting medium 115 between the runner stream and said side walls which medium is formed of a coating of chilled steel of a lesser temperature than the steel in the feeder stream of molten steel.

35. In the method of casting ingots the step which consists in pouring molten metal into the lowermost corner of an elongated horizontal prism-shaped matrix forwardly inclined to form an initial pool adjacent the incoming stream of metal, and chilling the 120 under portions of the pool.

36. An ingot mold for casting horizontal ingots comprising a pair of comple-

mental mold sections forming when assembled a horizontal closed mold having longitudinal joints of separation arranged one above the other on a diagonal of the matrix and with the upper joint downwardly inclined.

37. An ingot mold comprising a pair of

complemental mold sections to form when assembled a closed chill mold having longitudinal lines of separation at the corners of the mold matrix, diagonally extended lines of separation at one mold end, and transverse lines of separation at the other end.

JOHN EDMUND PERRY.
